UNITED STATES PATENT OFFICE

2,577,089

ADJUSTABLE BACK REST FOR CHAIRS

Peter Mondy, Detroit, Mich., assignor to Burroughs Adding Machine Company, Detroit, Mich., a corporation of Michigan

Original application April 5, 1947, Serial No. 739,553. Divided and this application October 2, 1948, Serial No. 52,503

5 Claims. (Cl. 155—158)

1

My invention relates generally to chairs and has to do particularly with a tiltable back rest adjustably mounted on a back-supporting frame to provide maximum comfort for the user of the chair.

This application is a division of my co-pending application, Serial No. 739,553, filed April 5, 1947, for "Adjustable Chair."

An object of my invention is to provide an improved chair of the foregoing character.

Another object is to provide an adjustable back rest for a chair which may be formed from a relatively small number of simple and inexpensive parts with a minimum of machined or close-fitting surfaces, and which may be assembled readily with a minimum of fitting or adjustment.

Another object is to provide a chair having a simple and strong back-rest cushion supporting mechanism which may be readily adjusted to a convenient height by the user and which permits rocking movement of the back cushion on its support for increased comfort of the user as he shifts his position in the chair.

Other objects and advantages of the invention will appear from the following description taken in conjunction with the appended drawings, wherein:

Figure 1 is a perspective view showing a chair constructed in accordance with my invention and with a portion of the tiltable back rest cut away showing one of its adjustable and pivotal support members;

Fig. 2 is an exploded perspective view showing the upper portion of the back-supporting frame of the chair shown in Fig. 1 with the tiltable back-rest cushion indicated in broken lines; and

Fig. 3 is a top plan view in partial section showing a portion of the tiltable back rest with the pivotal and adjustable means for supporting it on the upper portion of the chair back-supporting frame shown in Fig. 1.

A chair embodying the present invention is illustrated in Fig. 1 and comprises generally a base 10, a supporting post 11 rotatably mounted in the base 10, a seat 12 mounted on the seat-supporting post 11 and a back-supporting frame 13 extending upwardly at the rear of the seat 12 for adjustably supporting a bracket-unit A. The bracket-unit A is adapted to pivotally support a tiltable back-rest cushion 14 at adjusted heights convenient to the user of the chair.

The back-rest support or back-supporting frame 13 (Fig. 2), preferably formed of a light cast metal such as aluminum, supports two rods 15 disposed in parallel relation and secured to

2

bosses 13a formed near the top and on the inside portion of the back-supporting frame 13 by suitable fastening means, for example screws 16. Means is carried on the rods 15 for supporting the back cushion 14 at adjusted heights relative to the back frame 13 and seat cushion 12 for maximum comfort of the user. This means comprises a bracket 17 disposed on the front side of each rod 15 in slidably and adjusted clamped relation with its respective supporting rod. The brackets 17 are made integral with a cross-connecting bar 18 disposed transversely with and on the rear side of the rods 15, such as by a weld 18a whereby the brackets are fixed to the cross-connecting bar 18 in spaced relation at points on the brackets inwardly from the rods 15 to form the slideable bracket-unit A. Each bracket 17 has arcuately shaped portions 19 co-extensive with a portion of the front surface of the rods 15, whereby the brackets and cross-connecting bar 18 may be guided and maintained in fixed angular relation with the rods during their adjusting movement therealong. An ear element 20 projects outwardly from each bracket 17 and beyond the rods 15 and has a transverse opening adjacent its end for freely receiving the threaded end of a knurled-headed thumb-screw 21. The threaded end of the thumb-screw 21 is threadedly received in the end of an ear 22 provided by extending the cross-connecting bar 18 longitudinally in both directions to form arcuate portions 22a (Fig. 3) partially encircling the rear side of the rods 15 and terminating in the ears 22 which are disposed substantially parallel with the ears 20 and spaced rearwardly therefrom. Each bracket 17 is provided further with a forwardly directed arm 23 having a transverse opening 24 adjacent its front end to journal a pivot stud 25 secured in an ear formed on a bracket-plate 26. The bracket-plates 26 are provided at their tops and bottoms with an elongated opening 27 adapted to receive suitable fastening means, for example screws 28, for fastening the bracket-plate to a rear portion 29 of the cushion 14. This construction allows the back cushion 14 to be locked at an adjusted height above the seat cushion 12 simply by tightening the thumb-screws 21 in the adjusted position of the arcuate portions 19 and 22a along the rods 15 to cause these arcuate portions to be securely clamped to the rods and maintain the cushion 14 at a selected height where it is free to move angularly relative to the back frame 13 on the pivot studs 25.

Means are provided for adjusting the angular position of the back-rest cushion 14 relative to

the back-supporting frame 13, which includes rubber headed thumb-screws 30 carried in threaded collars 31 secured to the brackets 26. The brackets 26 are mounted on the back of the cushion 14 in a position so that the pivot studs 25 are located above the horizontal center line of the cushion 14 and the weight of the cushion below the said center line tends to maintain the cushion in a vertical position unless held otherwise out of this position by the rubber headed thumb-screws 30 contacting in the channel portion of the back-supporting frame 13. A rubber stop 32 secured to the back-supporting frame 13 adjacent the top and on the front surface thereof is adapted to be contacted by the back 29 of the cushion if the said cushion is rotated counterclockwise (Fig. 2) a sufficient extent on its pivot studs 25. The length of the lugs 23 and the rubber stop 32 is such that both the height and tilting adjustments are accessible to the user of the chair without danger of pinching the fingers or hands regardless of the angular position of the cushion which making said adjustments.

While I have shown and described herein one form of structure embodying my invention, it will be understood that changes in details and arrangements of parts may be resorted to without departing from the spirit of the invention.

I claim:

1. In a posture chair of the type having seat-supporting means and a back-supporting frame extending upwardly therefrom, the combination of a back rest mounting bracket unit having a rigid cross-bar and spaced arms extending forwardly therefrom, means supporting said mounting bracket unit on said frame for vertical sliding adjustment thereon, a back rest, spaced pivot members rigidly secured to said back rest and pivotally journaled in said arms respectively for pivotally mounting said back rest on said mounting bracket unit and rearwardly extending bumper elements carried on said back rest and positioned to abut said frame to limit pivotal movement of said back rest in one direction.

2. In a posture chair having seat-supporting means and a back rest supporting frame extending upwardly therefrom, a back rest, a back rest mounting bracket unit having a rigid cross-bar and spaced arms extending forwardly therefrom, means for supporting said bracket unit in vertical slidable relationship on said supporting frame and comprising a plurality of spaced guides mounted on said frame, means for locking said mounting bracket unit to said guides in adjusted relationship thereon, a plurality of bracket elements rigidly mounted on the back of said back rest and having studs secured therein for pivotally supporting said back rest to said first mounting bracket unit, an adjustable resilient stop supported on said back rest below the pivot axis of said studs to limit the pivotal movement of said back rest in one direction, and a resilient stop secured to the said supporting frame above the pivot axis of said studs to limit the pivotal movement of said back rest in the other direction.

3. In a chair having a back-supporting frame, a back rest, means on said frame for adjustably and pivotally supporting a back rest, said means comprising spaced parallel rods having their ends secured to said frame, a bar extending transverse to and disposed on one side of said rods with the ends thereof projecting beyond said rods and hav-

ing a threaded opening adjacent each of said projected ends, clamping elements integral with said bar and disposed on another side of said rods, each of said clamping elements having a first arm projecting therefrom, said first arm having an opening adjacent its end in axial alignment with the threaded opening in said bar, locking means disposed in said openings to clamp said clamping elements and said bar to said rods at selective positions along said rods, a second arm projecting forwardly from each of said clamping elements, brackets secured to the back of said back rest and supporting pivot elements journaled in said second arms respectively to pivotally support said back rest for angular movement relative to said frame, and an adjustable resilient stop supported on each of said brackets to limit the angular movement of said back rest in one direction and against said frame.

4. In a chair having a back-supporting frame, a back rest, spaced parallel elongate guides secured to said frame in vertically extending position and each spaced therefrom throughout a portion of its length, a bar extending transversely of said guides with the ends thereof projecting beyond said guides, clamping elements integral with said bar and disposed adjacent said guides, each of said clamping elements having a first arm projecting laterally therefrom in registry with the projecting ends of said bar respectively, locking means engaging said clamping elements and said bar to lock said bar on said guides at selected positions along said guides, a second arm projecting forwardly from each of said clamping elements, brackets secured to the back of said back rest pivotally connected to said second arms to support said back rest for locking movement relative to said frame, and a stop means to limit angular movement of said back rest in one direction and against said frame.

5. In a posture chair having seat-supporting means and a back rest supporting frame extending upwardly therefrom, a back rest, a back rest mounting bracket unit having a rigid cross-bar and spaced arms extending forwardly therefrom, means for supporting said bracket unit in vertical slidable relationship on said supporting frame and comprising a plurality of spaced elongate guides mounted on said frame, means including elongate clamp elements each partially embracing said guides respectively for locking said mounting bracket unit on said guides in adjusted relationship thereon, a plurality of bracket elements mounted on the back of said back rest and pivotally supporting said back rest on said mounting bracket unit, and resilient stop means on each of last said bracket elements to limit the pivotal movement of said back rest in either direction.

PETER MONDY.
